UNITED STATES PATENT OFFICE.

WILHELM GRIESSE, OF DENVER, COLORADO.

TANK CONSTRUCTION.

1,133,278.

Specification of Letters Patent. Patented Mar. 30, 1915.

Application filed May 15, 1911. Serial No. 627,323.

To all whom it may concern:

Be it known that I, WILHELM GRIESSE, a citizen of the United States, residing at Denver, in the county of Denver and State of Colorado, have invented new and useful Improvements in Tank Construction, of which the following is a specification.

The present invention has reference to tank construction, and more especially to tanks adapted for use in breweries for storing beer, which tanks, as is generally understood, are provided with an inner facing of enamel. Heretofore these tanks have been made round, being formed of so-called rings which were bolted together, the construction of the rings requiring the employment of costly machinery.

This invention comprehends the production of a storage tank whose component parts are constituted by metal sheets of uniform thickness, the sheets having their edges flanged so as to enable them to be bolted or riveted together after the application of the coating of enamel, all joints being located exteriorly of the tank.

The invention further comprehends certain improvements in or relating to the construction of the gas dome and the manhole door with which tanks of the type specified are ordinarily furnished.

A structural embodiment of the invention is illustrated in the accompanying drawings, whereof—

Figure 1 is a transverse, horizontal sectional view of the improved tank taken on the line 1—1 of Fig. 3; Fig. 2 is an enlarged fragmental sectional view illustrating a detail of the corner construction; Fig. 3 is a vertical section taken on the line 3—3 of Fig. 1; and Fig. 4 is an enlarged sectional view illustrative of the gas dome construction.

The tanks forming the subject of the present case are preferably built up and constructed upon a supporting foundation of concrete, as shown in said drawings, and they are also preferably provided with a concrete casing constituting an extension of the base or foundation and completely inclosing the tanks. Both foundation and casing may advantageously be reinforced by metal rods or the like which are embedded therein during the construction of the said foundation and casing.

The construction of the foundation is substantially as follows: A layer of suitable

concrete material 5 of the proper thickness is formed and in this layer is embedded a skeleton rectangular framework constituted by metal bars 6 and 7 arranged at right angles to each other. The surface of the layer is then covered with a layer 8 of insulating material of any preferred type, the insulating material being then covered with a further layer of concrete 9 in which there is likewise embedded a second reinforcing framework formed by the metal rods or bars 10 and 11. When the combined structure has been built up to the desired height, the previously constructed tank is mounted thereon.

The tank construction, as already stated, presents the most important features of this case, and the tanks themselves, as will be understood, may have any desired shape, that is to say, they may be either square or round, but preferably the former. In constructing the tanks, each member thereof may be formed of sheet metal, the sheets being of uniform thickness throughout and having their inner surfaces provided with a lining or facing. Where a tank member of multi-part construction is to be employed, the confronting edges of its two sections are formed with lateral flanges whose mutually-adjacent faces fit flush against each other, the two flanges being then fastened together.

Referring more particularly to Figs. 1 and 3 of the drawings, there is shown a square tank each of whose members consists of two connected sheets. The sheets 12^a, 12^b, constituting the bottom tank head 12, have their confronting inner longitudinal edges formed with depending flanges 12^c, which are bolted or riveted together. To anchor these sheets in the foundation they are also provided with a series of depending headed screws 12^d. The upper surfaces of said sheets are faced or coated with enamel.

The four sides of the tank 13, 14, 15 and 16, are in the main of counterpart construction and similar to the member 12 above described. Each of said members comprises a pair of sheets enameled on their inner faces and indicated by the same number as the corresponding main member with the super-added exponents. The opposed flanges on the inner longitudinal edges of the sections of each member are coextensive with said edges, project laterally outward and are bolted or riveted together; the lower ends of these flanges rest upon the edges of the

bottom member 12. The outer longitudinal edge of each section of each of the side members is also formed with a flange indicated by the corresponding number with the 5 exponent "e", which projects laterally outward and is disposed at an angle, as shown more particularly in Fig. 2. The arrangement of these angular flanges is such that they will abut directly against each other, as 10 shown in the figure last mentioned, a packing strip 17 being preferably interposed between the adjacent faces thereof. Said flanges are bolted or riveted together in the same manner as the inner flanges already described. Finally, the said sections of each 15 of said members are formed with out-turned lateral flanges at their top and bottom edges which are indicated by the corresponding numerals with the exponents "f" and "g". 20 The bottom flanges rest upon the adjacent edges of the bottom member 12, while the top flanges support the corresponding edges of the top member or head 18. The construction last mentioned may, however, 25 be slightly modified, as shown in Fig. 4, to the extent of providing the aforesaid top member 18 with marginal upstanding flanges 18^f which, in that instance, will fit flush against the upstanding straight edges 30 of the adjacent side members. The four side members and the top member are provided with anchoring studs or screws similar to the studs or screws 12^a, already referred to. These studs have their heads 35 embedded in the adjacent walls of the casing, which walls are built up in the same manner as the base or foundation after the tank has been set up.

By reason of the above construction, it 40 will be apparent that all joints are located exteriorly of the tank and, hence, the contents of the latter are in no danger of coming in contact with the bolts or rivets. The entire interior of the tank is covered by the 45 enamel coating, and, in consequence, the tank is rendered sanitary to a high degree.

One of the side members of the tank, in the present instance the member 15, is provided with a manhole, the adjacent portion 50 of the corresponding casing wall being cut away or removed to provide access thereto. The manhole construction is preferably as follows: An opening of the proper size is made in the aforesaid member 15, and the 55 edge of this opening is formed with an inwardly-extending lateral flange or collar 19, as shown in Fig. 3. The door 20, designed to close said opening, is in like manner formed with a continuous marginal flange 60 21 having a U-shaped cross section, the flange

14 being thus adapted to fit in the space between the walls of the said door flange 21. No hinges whatever are employed. Provision is also made in the top wall of the concrete casing for the extension of the gas 65 dome thereinto. The construction of this element is in the main similar to that of the manhole; that is to say, an opening is formed in the top member 18 of the tank and the metal around this opening is turned 70 up to form the annular flange 22 and the lower edge of the side wall of the dome proper 23 is fitted within flange 22, as shown in Fig. 4, the said dome wall and flange being then bolted or riveted together. 75

The usual tank adjuncts, such as the cooling coil and the piping system, are disposed within the tank and its casing in the ordinary or any preferred manner, the tank members being provided with perforations 80 at the proper points into which the pipes open. These adjuncts form on part of the present case and hence require no extended description.

As above stated, the vertical walls of the 85 casing are built up around the tank and over the top thereof, and said walls are internally reinforced and provided with insulating material. At the corners of the walls, the sets of vertical rods 24 are connected 90 by tie-wires 25, which are coiled or looped therearound in the manner shown in Fig. 1.

While the material with which the tank is lined is, in most instances, enamel, under certain circumstances it may be advisable to 95 utilize in lieu thereof thin sheets of copper or aluminum. The term "lining," employed in the appended claims, is, therefore, intended to cover both the metal lining and the facing or lining of enamel. 100

I claim as my invention:

A tank comprising connected top, bottom and side sheet metal members, a concrete casing inclosing said tank, and reinforcing means embedded in said casing consisting 105 of a series of inner and outer frames disposed adjacent the corresponding tank members and composed, each, of intersecting horizontal and vertical bars, the mutually-adjacent vertical bars at the corners of the 110 casing walls having connecting tie-wires looped therearound.

In testimony whereof I have hereunto set my hand in presence of two subscribing witnesses.

WILHELM GRIESSE.
